VALVE MECHANISM FOR HOISTING-ENGINES.

1,034,025.

Specification of Letters Patent.

Patented July 30, 1912.

Application filed September 8, 1908, Serial No. 452,104. Renewed December 21, 1911. Serial No. 667,209.

To all whom it may concern:

Be it known that I, SVEN T. NELSON, a citizen of the United States, and a resident of Chicago, county of Cook, and State of Illinois, have invented certain new and useful Improvements in Valve Mechanism for Hoisting-Engines, of which the following is a specification.

The invention relates to valve mechanism for hoisting or like engines which must be frequently started and stopped, and which must do the greatest amount of work in starting the load. For economical operation, a hoisting engine should be provided with valve mechanism that will admit steam for nearly the full length of the stroke of the engine piston when the engine is doing its greatest amount of work in starting the load. When the load is well started and the desired speed acquired, the valve mechanism should be arranged to reduce the cut-off to about one-fourth of the stroke, so that the steam may be economically utilized by expansion of the engine cylinder. Hoisting engines employed for heavy work, such as operating the cages or "skips" in the shafts of mines, are usually of the expensive, Corliss type in which the valve mechanism can be effectively controlled by the governor, so that the engine will take steam for the greater part of its stroke when slowly starting and the cut-off will be shortened when the desired speed is attained to thereby effect economical operation of the engine. Such engines are quite expensive and the slide valve mechanism of cheaper engines cannot be readily governor-controlled in this way.

The present invention seeks to provide simple and effective adjustable cut-off mechanism for a slide-valve engine so that it can take steam for nearly the full length of its stroke when starting and the point of cut-off be reduced when the desired speed is attained, and thereby adapt the cheaper slide-valve type of engine to meet the varying conditions under which a hoisting engine must be operated. The invention also seeks to provide means whereby the engineer can simultaneously control the adjustable cut-off mechanism and the throttle-valve of the engine with a single hand-lever or shifter.

The invention consists in the features of construction, combinations and arrange-

ments of parts hereinafter set forth, illustrated in the accompanying drawings and more particularly pointed out in the appended claims.

In the drawings, Figure 1 is a view in elevation of a slide-valve engine with the present invention applied thereto. Fig. 2 is a plan view of the same. Fig. 3 is a view in elevation on an enlarged scale of the valve mechanism with the cover of the valve chest removed and certain parts shown in central, vertical section. Fig. 4 is a view in central, horizontal section of the parts shown in Fig. 3. Fig. 5 is a detail section on line 5-5 of Fig. 4. Fig. 6 is a view similar to Fig. 3 illustrating a modification of the invention.

The engine frame 10 may be of any suitable construction. At one end it is connected to the engine cylinder 11 and at its opposite end it is provided with a bearing 12 for the engine crank-shaft 13. A crank 14 on the shaft is coupled to a connecting rod 15 which is coupled at its inner end to a suitable cross-head 16. The cross-head (see Fig. 4) is connected as usual to the piston 17 of the engine by a piston-rod 18. The valve chest 19 of the engine is arranged on one side of the cylinder and is provided with a suitable seat 20 for a reciprocating slide-valve 21. Steam passages as usual, lead from the valve seat to the opposite ends of the engine cylinder 11 and an exhaust passage 23 opens through the valve seat between the ends of the steam passages 22. The slide-valve 21 is provided as usual with inlet ports 24 and an exhaust cavity 25 for controlling the flow of steam to and from the opposite ends of the engine cylinder 11. A valve-rod 26 connected to the main slide valve 21, extends through a stuffing-box 27 in the end wall of the valve chest and is connected to a slide 28 that is guided in a suitable box 29 on the side of the engine frame. The forward end of the slide 28 (see Figs. 1 and 2) is connected by a link 30 to the inner arm 31 of the rocker 32. The rocker 32 is mounted on a shaft 33 carried by a bracket 34 on the side of the engine frame. The outer arm 35 of the rocker is connected by a pin 36 to a block 37 that is engaged by a link 38. A pair of eccentrics 39 on the engine shaft 13 are connected by eccentric straps 40 and rods 41 to the opposite ends of the link 38. A cross-piece 110

42 on the face of the link is provided with a projecting pin 43 by which the link is connected to the reversing lever. This reversible valve mechanism is of the well-known 5 Stephenson link type and need not be more fully described. Other forms of reversible valve mechanism may be employed without departure from the essentials of the invention.

10 The main slide-valve is provided at its side edges with outwardly-projecting lugs 44 (see Fig. 3) which carry a balancing plate 45 (see Fig. 4) that is seated within a slide 46. The latter moves upon a suitable 15 seat formed on the valve chest cover 47. A throttle-valve casing 48 is mounted upon the valve chest 19 and communicates therewith, as shown in Fig. 3. A suitable throttle valve 49 arranged within the casing, is provided with a stem 50 that projects through a suitable stuffing-box 51, and is connected to an operating crank-arm 52. The crank-arm 52 is fixed to a short, horizontal shaft 53 journaled in lugs 54 that project from the 20 throttle valve casing. An arm 55 on the shaft 53 is connected by a rod 56 to an arm 57 on a shaft 58. This shaft is journaled in suitable brackets 59 and is provided with an operating hand-lever or shifter 60 by which 25 the operator may open and close the throttle valve 49 to admit a supply of steam to the engine valve chest or cut it off therefrom and thus start and stop the engine.

An auxiliary cut-off valve of the Meyer 30 type is employed in connection with the main slide-valve 21. This auxiliary cut-off valve comprises two sections 61 and 62 arranged on the back of the main slide-valve and between it and the balancing plate 45.

40 A tubular valve-rod 63 extends through a stuffing-box 64 in the end of the valve chest and its end portion extends through an opening in a lug on the auxiliary valve section 61. Nuts 65 are threaded upon the 45 tubular valve-rod on opposite sides of the valve section 61 and securely connect the latter to the rod. The outer end of the tubular valve-rod 63 is provided with a stuffing-box 66 and an inner, solid valve-rod 68 extends 50 through the stuffing-box and through the tubular valve-rod and also through a perforated lug on the back of the auxiliary valve section 62. Nuts 69 are threaded upon a screw portion 70 of the valve-rod 68 on opposite sides of the lug on the back of the valve section 62, and securely connect the valve section to the rod. The inner end of the valve-rod 68 extends within a sleeve 71 that is secured in position within an opening 55 in the end wall of the valve chest 19. An upwardly projecting clip 72 is adjustably threaded upon the outer end of the tubular valve-rod 63 and is held in place thereon by a lock-nut 73. A downwardly projecting clip 74 (see Fig. 5) is adjustably threaded 60 upon the outer end of the solid valve-rod 68 and is secured in position thereon by a lock-out 75. The clips 72 and 74 are respectively connected by links 76 and 77 to the oppositely disposed arms of a T-shaped lever 78. This lever is pivotally connected by a pin 79 to the end of a reciprocating member or slide 80 arranged in guideways in the box 29. A pin 81 on the slide 80 projects outwardly through a slot 82 in the face of the box 29 and is connected by a rod 83 to an eccentric strap 84 (see Fig. 2) which engages a third eccentric on the engine shaft 13. By this means, the slide 80 and the valve-rods 63 and 68 connected thereto through the medium of the lever 78 and links 76 and 77 are reciprocated to reciprocate the auxiliary valve sections 61 and 62 that control the inlet ports 24 of the main slide-valve 21 and determine the point of cut-off. By rocking the T-shaped lever 78 about its pivot-pin 79, the valve-rods 63 and 68 and the auxiliary valve sections 61 and 62 can be adjusted relatively to the operating means therefor and the valve sections moved to and from each other to vary the point of cut-off. The outer end of the valve-rod 68 is guided within an opening 85 (see Fig. 5) in the end of the slide 80 and within which it slides when the T-lever 78 is rocked upon its pivot 79.

The adjustment of the auxiliary valve-sections 61 and 62 is preferably effected by an auxiliary motor comprising a small engine cylinder 86 which is mounted upon the frame 10 of the engine. A piston 87 within the auxiliary cylinder 86 is connected by a piston-rod 88 and a link 89 to the upwardly projecting arm of a shifter or bell-crank 90. This shifter or bell-crank is pivotally mounted upon a bracket 91 and its horizontal arm is connected by a pivot pin 92 to the lower end of a link 93. The upper end of the link 93 is connected by a pivot pin 94 to the central, horizontal arm of the T-lever 78. A slide-valve 95 within the steam chest 96 of the auxiliary cylinder 86 controls the steam and exhaust ports 97 and 98 and the flow of steam or other motive fluid under pressure through said ports and to and from the opposite ends of the cylinder. Means are provided whereby the operator may manually shift the valve 95 to admit steam to either end of the auxiliary cylinder 86 and thereby shift the piston 87 to one or the other end of this movement. When the valve 95 is in the position shown in the drawings, the piston 87 will be held against the right-hand end or head of the auxiliary cylinder 86 and the T-shaped arm will be held by the connections between it and the piston 87 in such a position that the auxiliary valve sections 61 and 62 are close together. The flow of steam through the inlet ports 24 of the main slide-valve, in this position of the 110

115 120 125 130

parts, will not be cut off by the auxiliary valve sections until the engine piston 17 is near the end of its stroke. In starting the engine, the operator will, by shifting the valve 95, place the parts of the valve mechanism in the position shown in the drawings, so that the engine will take steam for nearly the full length of the stroke. When the load is started and the amount of work required of the engine thus cut down, the operator will shift the valve 95 to admit steam to the right-hand end of the auxiliary cylinder 86, so that the piston 88 will be moved to the left-hand end of the cylinder. This movement of the piston will rock the T-lever 78 upon its pivot 79 and thereby shift the valve-rods 63 and 68 and move the auxiliary valve sections 61 and 62 apart and the flow of steam to the engine cylinder 11 will then be cut off at about one-quarter stroke, so that the steam will be economically utilized by expansion in the cylinder. In either position of the piston, the bell-crank 90 is of course held against substantial movement. The link 93, however, will rock back and forth upon the pivot pin 92 as the slide 80 and parts connected thereto are reciprocated.

The ends or heads of the small auxiliary cylinder 86 act as stops to limit the movement of the piston 88 and the relative adjustment of the auxiliary valve sections 61 and 62. The position of the auxiliary valve sections at the limits of their relative adjustment, may be varied as desired by adjusting the valve rods 63 and 68 relatively to the clips 72 and 74 by which the rods are connected to the links 76 and 77 of the valve shifting devices. The shifter or hand-lever 60 which controls the throttle valve is also preferably arranged to control the adjusting means for the auxiliary valve sections 61 and 62. For this purpose, the shaft 58 is provided with an upwardly projecting arm 99 which is connected to the rear end of a rod 100. The forward end of the rod is provided with an elongated slot 101 which engages a pin 102 upon the lower end of an arm 103. The upper end of this arm is connected to a short shaft 104 that is journaled on a bracket 105 projecting from the auxiliary cylinder 86. A short crank-arm 106 upon the inner end of the shaft 104 is connected by a link 107 to the stem 108 of the valve 95.

In the position of the hand-lever or shifter 60 shown in the drawings, the throttle-valve 49 is closed. To open the throttle valve the lever is moved in the direction indicated by the arrow in Fig. 3. In the closed position of the throttle valve the rod 100 that is connected to the throttle valve shifter, will hold the valve 95 of the auxiliary cylinder 86 in position to admit steam to the left-hand end of the cylinder and hold the piston at the

right-hand end of its movement, as shown, with the auxiliary valve sections 61 and 62 near one another, so that the point of cut-off will be near the end of the stroke of the engine. In this position of the parts, the pin 102 on the lever 103 will be at the left-hand end of the slot 101 in the rod 100. This lost motion connection between the arm 103 and the rod 102 permits a partial shift of the lever or shifter 60 before the arm 103 is moved. In starting the engine, the operator will move the lever 60 through a portion of its full movement to open the throttle valve 49 and admit steam to the steam chest 19. This part movement of the lever 60 will merely serve to take up the lost motion between the rod 100 and the arm 103 so that the valve 95 and the piston 87 of the auxiliary engine will remain in position and the auxiliary cut-off valve sections 61 and 62 will be so operated that the engine will take steam for nearly the full length of its stroke to start the load. After the load is started and the work required of the engine reduced, the operator will complete the shift of the lever 60 to fully open the throttle valve and thereby, through the medium of the rod 100 and arm 103, will shift the valve 95 to admit steam to the right-hand end of the auxiliary cylinder 86. The piston 87 therein will then be shifted to its left-hand end and the cut-off valve sections 61 and 62 will be moved apart so as to cut off the flow of steam to the inlet ports 24 of the main slide valve 21 when the engine piston has traveled through about one-quarter of its stroke. When the operator shifts the lever 60 back to the position shown in the drawings to close the throttle valve and stop the engine, the valve 95 will be shifted so that the piston 87 is moved back to the right-hand end of the cylinder 86 and the auxiliary cut-off valve sections 60 and 61 are moved together so as to effect a long cut-off when the engine is again started.

It will be understood that, as usual in hoisting engines, there will be a pair of engines, one coupled to each end of the shaft 13 with their cranks arranged at an angle of ninety degrees to each other so that there will be no dead center and the engines can be started from any point. The two engines will be duplicates of each other and the shaft 58 will be connected to the throttle valve or valves and to the cut-off adjusting devices of both engines. The single hand-lever or shifter 60 on the shaft 58 will thus simultaneously control the operation of the two engines.

In the modification illustrated in Fig. 6, the adjustable valve sections 61 and 62 are connected to two solid valve rods 109 and 110 which are arranged side by side and extend through two stuffing-boxes 111 in the end wall of the steam chest. The valve rods

109 and 110 extend through openings in lugs on the back of the valve sections 61 and 62. The valve rod 109 extends loosely through the lug on the valve section 62 but is secured 5 to the valve section 61 by nuts 112 threaded on a screw portion 113 thereof on opposite sides of the valve section 61. In a similar manner, the valve rod 110 extends loosely through the lug on the back of the valve 10 section 61 and is secured to the lug on the back of the valve section 62. A pair of clips 114 are adjustably threaded upon the outer ends of the valve rods 109 and 110 and are secured in position by lock-nuts 115. These 15 clips are connected by links 116 to the upper and lower arms of the T-shaped lever 78. The opposite ends of the valve rods are guided in a sleeve or bushing 117 fixed to the outer end wall of the steam chest 19. 20 The other parts are similar to those previously described and the operation is the same.

It is obvious that numerous changes may be made in the details set forth without departing from the essentials of the invention 25 as defined in the claims.

I claim as my invention:—

1. In a hoisting engine, the combination with the engine cylinder, of a main valve 30 therefor driven by the engine and having inlet and exhaust ports, an auxiliary cut-off valve comprising two sections controlling the inlet ports of said main valve, separate valve rods connected to said auxiliary valve 35 sections, means driven by the engine for operating said valve rods and said auxiliary valve sections, means for adjusting said rods and said valve sections to vary the point of cut-off, an auxiliary motor for throwing 40 said adjusting means to the opposite ends of its movement, substantially as described.

2. In a hoisting engine, the combination with the engine cylinder, of a main valve therefor driven by the engine and having inlet and exhaust ports, an auxiliary cut-off valve comprising two sections controlling the inlet ports of said main valve, separate rods connected to said auxiliary valve sections, a member driven by the engine for operating 45 said rods and valve sections, an auxiliary engine cylinder, a piston therein, means operated by said piston for shifting said rods to adjust said auxiliary valve sections to and from each other and a manually operated valve mechanism controlling the flow of motive fluid to and from said auxiliary cylinder to throw said piston and said adjusting means to the opposite ends of their movement, substantially as described.

60 3. In a hoisting engine, the combination with the engine cylinder, of a main valve therefor driven by the engine and having inlet and exhaust ports, an auxiliary cut-off valve comprising two sections controlling 65 the inlet ports of said main valve, separate

valve rods connected to said sections, means driven by the engine for operating said rods and valve sections, a throttle valve for the engine, a shifter for said throttle valve, and means operated by said shifter for adjusting said rods and valve sections to vary the point of cut-off, substantially as described. 70

4. In a hoisting engine, the combination with the engine cylinder, of a main valve therefor driven by the engine and having 75 inlet and exhaust ports, an auxiliary cut-off valve comprising two sections controlling the inlet ports of said main valve, separate valve rods connected to said sections, a member driven by the engine for operating said 80 rods and valve sections, a throttle valve for the engine, a shifter for said throttle valve, means operated by said shifter after a predetermined movement thereof for moving said rods relatively to said member to adjust 85 said auxiliary valve sections to and from each other, substantially as described.

5. In a hoisting engine, the combination with the engine cylinder, a main valve therefor driven by the engine and having inlet 90 and exhaust ports, an auxiliary cut-off valve comprising two sections controlling the inlet ports of said main valve, separate valve rods connected to said sections, means driven by the engine for operating said rods and 95 valve sections, an auxiliary motor, means operated by said auxiliary motor for adjusting said rods and valve sections to vary the point of cut-off, a throttle valve for the engine, a shifter for said throttle valve, and 100 valve mechanism for said auxiliary motor controlled by said shifter, substantially as described.

6. In a hoisting engine, the combination with the engine cylinder, of a main valve 105 therefor driven by the engine and having inlet and exhaust ports, an auxiliary cut-off valve comprising two sections controlling the inlet ports of said main valve, separate valve rods connected to said sections, a member driven by the engine for operating said 110 rods and valve sections, an auxiliary engine cylinder, a piston in said cylinder, means operated by said piston for moving said valve rods relatively to said member to adjust said auxiliary valve sections to and from each other, a throttle valve for the main engine, a shifter for said throttle valve, valve mechanism controlling the flow of motor fluid to and from said auxiliary cylinder, and lost-motion connections between said valve mechanism and said shifter, substantially as described. 120

7. In a hoisting engine, the combination with the engine cylinder, of a main slide valve therefor having inlet and exhaust ports, reversible valve mechanism driven by the engine for reciprocating said main slide valve, an auxiliary cut-off valve comprising 125 two sections on the back of said main valve 130

engine cylinder, a piston therein operatively connected to said adjusting means, a throttle valve for the main engine, a shifter for said throttle valve and valve mechanism for 5 said auxiliary cylinder connected to said shifter, substantially as described.

14. In a hoisting engine, the combination with the engine cylinder, of a main slide valve therefor driven by the engine and 10 having inlet and exhaust ports, an auxiliary cut-off valve comprising two sections controlling the inlet ports of said main valve, separate valve rods connected to said sections, a reciprocating member driven by the 15 engine for reciprocating said valve rods and auxiliary valve sections, shiftable connections between said reciprocating member and said valve rods, and adjusting means for shifting said connections and valve rods 20 during the operation of the engine to move said auxiliary sections to and from each other to vary the point of cut-off, said connections being adjustable independently of said adjusting means, to adjust said valve 25 sections relatively to said adjusting means, substantially as described.

15. In a hoisting engine, the combination with the engine cylinder, of a main slide valve therefor driven by the engine and having 30 inlet and exhaust ports, an auxiliary cut-off valve comprising two sections controlling the inlet ports of said main valve, separate valve rods connected to said sections, a reciprocating member driven by the 35 engine for reciprocating said rods and valve sections, shiftable connections between said reciprocating member and said valve rods, adjusting means for shifting said connections and valve rods during the operation of 40 the engine to move said valve sections to and from each other, said shiftable connections being adjustable independently of said adjusting means to vary the position of said valve sections relatively to said adjusting 45 means, a throttle valve for the engine, a shifter for said throttle valve and means actuated thereby for operating said adjusting means, substantially as described.

16. In a hoisting engine, the combination 50 with the engine cylinder, of a main slide valve therefor driven by the engine and having inlet and exhaust ports, an auxiliary cut-off valve comprising two sections controlling the inlet ports of said main slide 55 valve, separate valve rods connected to said sections, a reciprocating member driven by the engine for reciprocating said rods and valve sections, shiftable connections between said member and said valve rods, adjusting 60 means for shifting said connections and valve rods during the operation of the engine to move said valve sections to and from each other, means for adjusting said shiftable connections independently of said adjusting 65 means to vary the position of said

valve sections relative to said adjusting means, an auxiliary engine cylinder, a piston in said cylinder operatively connected to said adjusting means and manually operated valve mechanism for said auxiliary engine cylinder to throw said piston and said adjusting means to the opposite ends of their movement, substantially as described. 70

17. In a hoisting engine, the combination 75 with the engine cylinder, of a main slide valve therefor driven by the engine and having inlet and exhaust ports, an auxiliary cut-off valve comprising two sections controlling the inlet ports of said main valve, separate valve rods connected to said sections, a reciprocating member driven by the 80 engine, a lever pivoted on said member and connected on opposite sides of its pivot to said valve rods, a shifter for moving said lever and valve rods during the operation of the engine to adjust said valve sections to and from each other, an auxiliary motor for operating said shifter and manually operated means controlling said auxiliary motor 85 to throw said piston and said adjusting means to the opposite ends of their movement, substantially as described. 90

18. In a hoisting engine, the combination with the engine cylinder, of a main slide valve therefor having inlet and exhaust ports, reversible valve mechanism driven by the engine for reciprocating said main slide valve, an auxiliary cut-off valve comprising two sections on the back of said main valve and controlling the inlet ports thereof, separate valve rods connected to said sections, a reciprocating member driven by the engine, a lever pivoted to said member and connected on opposite sides of its pivot to said valve rods, a shifter for moving said lever and valve rods during the operation of the engine to adjust said valve sections to and from each other, an auxiliary engine cylinder, a piston in said cylinder oppositely connected to said shifter, valve mechanism controlling the flow of motor fluid to and from said auxiliary cylinder to throw said piston and said adjusting means to the opposite ends of their movement, and a hand-lever 105 controlling said valve mechanism, substantially as described. 110

19. In a hoisting engine, the combination with the engine cylinder, of a main slide valve therefor driven by the engine and having inlet and exhaust ports, an auxiliary cut-off valve comprising two sections controlling the inlet ports of said main valve, separate valve rods connected to said sections, a reciprocating member driven by the 120 engine, a lever pivoted on said member and connected on opposite sides of its pivot to said valve rods, a shifter for moving said arm and said valve rods to adjust said auxiliary valve said sections to and from each 125 130

other, a throttle valve for the engine, a lever for operating said throttle valve, and means operated by said throttle lever after a predetermined movement thereof for actuating 5 said adjusting shifter, substantially as described.

20. In a hoisting engine, the combination with the engine cylinder, of a main slide valve therefor driven by the engine and having 10 inlet and exhaust ports, an auxiliary cut-off valve comprising two sections controlling the inlet ports of said main valve, separate valve rods connected to said sections, a reciprocating member driven by the 15 engine, a lever pivoted on said member and connected on opposite sides of its pivot to said valve rods, a shifter for moving said lever and valve rods to adjust said valve sections to and from each other, an auxiliary 20 engine cylinder, a piston therein operatively connected to said shifter, a throttle valve for the main engine, an operating lever for said throttle valve, valve mechanism for said auxiliary cylinder, and operating, lost-motion 25 connections between said valve mechanism and said throttle lever, substantially as described.

21. In a hoisting engine, the combination with the engine cylinder, of a main slide 30 valve therefor driven by the engine having inlet and exhaust ports, an auxiliary

cut-off valve comprising two sections controlling the inlet ports of said main valve, separate valve rods connected to said sections, a reciprocating member driven by the 35 engine, a lever pivoted between its ends upon said reciprocating member, adjustable connections between the opposite ends of said lever and said valve rods, a shifter for said lever and a link connecting said shifter and 40 said lever, substantially as described.

22. In a hoisting engine, the combination with the engine cylinder, of a main valve therefor driven by the engine and having 45 inlet and exhaust ports, an auxiliary cut-off valve comprising two sections controlling the inlet ports of said main valve, a tubular valve rod connected to one of said valve sections, a second valve rod connected to the other section and extending through 50 said tubular valve rod, a member driven by the engine for reciprocating said rods and valve sections, adjustable connections between said member and said valve rods and means for shifting said connections and rods 55 to adjust said auxiliary valve sections and vary the point of cut-off, substantially as described.

SVEN T. NELSON.
